UNITED STATES PATENT OFFICE

99,859

DESIGN FOR A TEXTILE FABRIC

Curt Erwin Forstmann, Montclair, N. J.

Application October 12, 1935, Serial No. 58,968

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part thereof.

In the drawing, the sole figure of which is a plan view of a piece of the textile fabric embodying the design of the present invention, the cloth depicted is of a single color.

The design is a pattern of diagonal stripes each comprising a series of parallelogram-shaped elevations with their long sides extending weftwise of the fabric, said elevations being irregular both in outline and contour, giving the fabric a rippled appearance.

I claim:

The ornamental design for a textile fabric as shown and described.

CURT ERWIN FORSTMANN.
